Fig-4.

Fig. 5.

A technical line drawing of a rectangular component, likely made of metal. It features a central slot with a cross-hatch pattern. A threaded rod (part 25) is inserted into the right side of the slot. A small hole is visible on the top surface near the slot. The component is shown at an angle, with a reference line labeled 'F' extending from its top right corner.

UNITED STATES PATENT OFFICE.

WILLIAM J. SEELEY, OF KANSAS CITY, MISSOURI.

HOLLOW METAL TIE.

1,112,330.

Specification of Letters Patent. Patented Sept. 29, 1914.

Application filed March 18, 1914. Serial No. 825,493.

To all whom it may concern:

Be it known that I, WILLIAM JAMES SEELEY, a citizen of the United States, residing at Kansas City, in the county of Jackson and State of Missouri, have invented certain new and useful Improvements in Hollow Metal Ties; and I do hereby declare the following to be a full, clear, and exact description of the invention, such as will enable others skilled in the art to which it appertains to make and use the same.

An object of this invention is the provision of a metallic railway tie of hollow formation and having improved rail base clamping means reliably and adjustably secured thereto.

Another object is the provision of cushions interposed between the metallic tie and the clamping members adjustable with the latter.

With these and other objects in view, the invention consists in the novel construction, arrangement and formation of parts as will be hereinafter specifically described, claimed and illustrated in the accompanying drawings, in which,

Figure 1 represents a top plan view of a railway tie constructed in accordance with my invention. Fig. 2 represents a side elevation thereof partly broken away. Fig. 3 represents a longitudinal sectional view, partly broken away. Figs. 4 and 5 represent perspective views of the clamping members constituting a pair, and Fig. 6 represents a perspective view of the anchoring bar for the clamping member, partly broken away.

Referring to the drawing in detail, where-
40 in similar reference numerals designate cor-
responding parts throughout the several
views, the numeral 10 indicates the bottom
of the metal tie on which are formed inte-
gral side walls 11 and end walls 12 having
45 apertures 13 therein and a top 14. The
medial portion 15 of the tie is depressed as
shown in Fig. 3.

Cushion blocks 16 of wood or other yield-
able material are disposed upon the ele-
50 vated end portions 14 of the top, and are
formed with vertical openings 17 register-
ing with openings 18 formed in the top 14
and elongated on a longitudinal line of the

latter. A rail base clamping device comprising a pair of members 19 and 20 is disposed over each cushion block 16, and, as shown in Figs. 4 and 5, the members 19 and 20 are stamped from sheet metal of adequate thickness. Each of the members 19 and 20 is substantially rectangular in shape and is formed with integral oppositely directed ears or extensions 21, having apertures 22 therethrough. Tongues 23 are also formed on each of the members at opposite ends thereof and are bent over in spaced relation to the main body thereof. The member 19 is adapted to be disposed over the member 20, and in order that the tongues 23 of the respective plates lie in the same plane, the tongues of the latter member 20 are spaced a greater distance from the body thereof.

When properly positioned, the apertures 22 of the top and bottom clamping members 19 and 20 are in registration and threaded bolts 24 having heads 25 are positioned through the apertures 22 and openings 17 and 18. The heads 25 of the bolts are disposed against the base 26 of the rail on the portions of the latter exposed between the tongues 23 of each of the members 19 and 20. An anchoring bar 27 is disposed under each elevated end 14 of the tie and is formed with a pair of spaced threaded apertures in which the lower ends of the bolts 24 are screwed. 85 The opposite offset ends 28 of the bar 27 are rounded and screw threaded and positioned through the suitable apertures formed in the end wall 12 and the vertical portion 29 formed at the junction of the depressed portion 15 and top part 14 of the top of the tie. Nuts 30 are threaded on the ends 28 and firmly engage against the vertical walls 12 and 29 to lock the anchoring bar 27 and coöperating parts in operative position. 95

The rails 32 may be adjusted to provide a track of the desired gage by adjusting the anchoring bar 27 longitudinally of the tie, subsequently to loosening the bolts 24. After the proper adjustment of the rails is 100 made the nuts 30 are screwed tightly against their seats and the bolts 24 again tightened. If desired, the cushioning blocks 16 may be dispensed with, and the rail base clamping members 19 and 20 engaged directly 105 on the top of the metal tie.

What I claim is:—

A railway tie comprising a body, cushions disposed over the ends of said body, pairs of rail base clamping members disposed over said cushions, securing bolts extending through said rail base clamping members and cushions, means for anchoring said securing means, and means for adjust-

ing said anchoring means longitudinally of said tie.

In testimony whereof I affix my signature in presence of two witnesses.

WILLIAM J. SEELEY.
